UNITED STATES PATENT OFFICE.

JOHN B. CROCKER, OF ST. LOUIS, MISSOURI, ASSIGNOR TO JOHN W. THOMAS
AND JOHN B. SEGHERS, JR., BOTH OF CHICAGO, ILLINOIS.

STOVE.

SPECIFICATION forming part of Letters Patent No. 314,286, dated March 24, 1885.

Application filed February 23, 1884. (No mode.)

To all whom it may concern:

Be it known that I, JOHN B. CROCKER, residing in the city and county of St. Louis, in the State of Missouri, have invented certain new and useful Improvements in Stoves, as set forth in the following specification.

The object of my invention is to provide means for introducing a current of external air into the oven during the process of cooking and for removing the impure gases and odors evolved in an oven during said process without unnecessary waste or shrinkage in the article being cooked, and retaining the nutritive elements in the food being prepared, and for cooking the same rapidly and thoroughly with a saving of fuel; and my invention consists in the means hereinafter set forth and claimed.

I am aware that mechanisms have been heretofore patented and used for introducing external air into the oven and for distributing the same more or less throughout the oven, and communications have also been heretofore made between the oven and the ascending flue. The devices, however, heretofore patented and used for these purposes have been defective, first, as to the introduction of the external air, in that either they have not supplied a sufficient quantity, or, on the contrary, by making too large radial openings in the oven-door, they have supplied too great a quantity, and have been defective, secondly, in not properly and economically distributing the external air at the proper points and in the proper manner in the oven; and, third, have further been defective, so far as they have taken the impure gases into the chimney-flue, in this, that they have been so arranged as that the soot from the flue would descend into the oven.

In the drawings, Figure 1 is a front elevation of a range or stove, with the door partially

broken away and showing four of the air-distributing pipes. Fig. 2 is a perspective view of a stove without its oven-door, showing the interior of the oven and the partition which separates the oven from the flue. Fig. 3 is a vertical section of the door, showing one method of applying said air-distributing pipes.

A represents the door of the oven, in which, preferably at the very center, C, are secured the air-distributing pipes *a a a* in any convenient manner. Said pipes are open at both ends and take external air at the aperture C, and conduct the same to different parts of the oven, as desired, the inner ends of some of said pipes being bent, as shown in Fig. 3.

In the partition which separates the oven from the chimney-flue at J J, Fig. 2, is shown a rotoscope or register, *w w*, for the purpose hereinabove set forth.

Among the advantages arising from the use of said pipes, are that a uniform temperature may be maintained at all parts of the oven, and, further, that the external air is thereby heated to some extent before being introduced, at least to the extent of taking whatever chill there may be from the same.

I claim—

1. In an oven, air-distributing pipes for external air radiating from a central point in the oven-door, substantially as and for the purpose set forth.

2. The combination, in an oven, of radiating air-distributing pipes, substantially as described, with a rotoscope or register in the partition separating the oven and the flue, substantially as and for the purpose set forth.

JOHN B. CROCKER.
